GAS AND LIQUID CONTACT APPARATUS

Filed Sept. 14, 1928

Attorneys

UNITED STATES PATENT OFFICE

FREDERICK H. WAGNER, OF BALTIMORE, MARYLAND, ASSIGNOR TO THE BARTLETT HAYWARD COMPANY, OF BALTIMORE, MARYLAND, A CORPORATION OF MARYLAND

GAS AND LIQUID CONTACT APPARATUS

Application filed September 14, 1928. Serial No. 305,977.

This invention pertains to gas and liquid contact apparatus and more particularly to apparatus for treating, washing or cleaning a gas with a liquid.

5 In general terms, it is an object of the invention to improve the construction and efficiency of operation of apparatus of this character.

Another object of the invention is to provide a washer or scrubber having a single compact rotative element adapted to beat or mix the contacting liquids and gases and to propel the gases toward the gas outlet. The rotative element referred to may also be arranged to effect a separation of the liquid particles entrained by the gases before discharging the gases through the outlet.

A further object of the invention is to provide, in apparatus of the character described, 20 a screening member so disposed as to control and distribute the flow of the gases and aid in effecting a rapid and complete scrubbing or contacting of the gases with the liquid.

Apparatus embodying the invention is illustrated in the accompanying drawings, wherein,—

Fig. 1 is a side elevational view of a washer having the rotative element thereof pivoted on a horizontal axis, a portion of the external 30 casing being broken away to show the construction of the fan or blower.

Fig. 2 is a cross section taken on the line II—II of Fig. 1.

Fig. 3 is a detail view to an enlarged scale 35 of the adjustable spray nozzle.

Referring to the drawings the apparatus comprises a cylindrical casing 1, which may be cast or constructed in section as indicated, having opposed central inlet openings 2 and 3 for the gases to be cleaned or treated and a peripheral outlet 4; a rotative element 5 carrying beater arms 6 and fan blades 7; and liquid spray nozzles 8 connected through manifolds or chambers 9 to supply pipes 10.

40 The casing 1 is mounted upon standards or supporting members 11. The rotative element 5 is disposed in the center of the casing 1 and, being substantially disk-shaped, divides the interior of the casing into two similar sections or chambers. The rotative ele-

ment is mounted upon a shaft 15 which is supported in any suitable manner, as upon the bearings 16 carried by the central portions of the casing 1. Stuffing boxes 17 may be provided where the shaft 15 passes through the shell of the casing.

Two cylindrical foraminous partitions or screens 18 are arranged on opposite sides of the rotative element 5. In the construction illustrated the screens 18 are supported by the side walls of the casing, but if desired they may be similarly secured to the member 5 to rotate therewith. The screens are symmetrically disposed about the shaft 15 and define gas-receiving chambers 19 adjacent to the inlet openings 2 and 3. Between the walls of the casing 1, the screens 18 and the rotative member 5 are the washing or treating chambers 20 in which the beater arms 6 and spray nozzles 8 are disposed.

The beater arms 6 are secured in any suitable manner to the rotative element 5 to rotate therewith and project laterally from the rotative element into the path of the gases traversing the chamber 20. The spray nozzles 8 are mounted upon the shell of the casing and project inwardly adjacent to the beater arms 6.

The specific form and arrangement of the beater arms and spray nozzles may be variously modified without departing from the scope of the invention, the latter being preferably adjustable in order that the spray may be controlled. A form of nozzle that may be utilized is shown in detail in Fig. 3.

Referring to this figure, the body portion of the nozzle comprises a hollow slotted or spiral member 21, the inner end of which is in communication with the manifold 9.

It will be apparent that liquid admitted under pressure to the manifold 9 will issue through the spaces between the convolutions of the spiral 21 to form a uniformly distributed spray in sheet form around the nozzle throughout its entire length. The outer end of the spiral 21 is closed by a block 22 carried on a centrally disposed rod 23. The end of the rod may be threaded, as shown, and a clamping nut 24 provided to engage the block 22. The outer end of the rod 23 projects

through a stuffing-box 25 and a bracket 26, and a threaded thumb-nut 27 is disposed on said end of the rod. The thumb-nut 27 is adapted to engage the bracket 26 and therefore by exert pressure upon the spiral 2 through the rod 23 and block 22 to alter the spacing between the convolutions of the spiral through which the washing fluid issues. Such construction throws out the spray in spiral sheet form and the spirals may be opened wide to clean themselves as well as the adjacent elements. In this way clogging up of the apparatus is prevented.

The rotative member 5 carrying the beater arms 6 extending into the chamber 20 is also provided at its periphery with fan blades 7 conforming in shape to the outline of the casing. The casing however extends beyond the fan blades and forms a gas-receiving pocket 28 extending around the entire periphery and merging at the bottom into the outlet 4. The tips of the fan blades are bent, as shown in Fig. 1, to deflect and discharge the particles of water or washing liquid contained in the gases laterally through the openings 29 into the channels or recesses 30 which may be cast integral with the casing. Drainage from the channels 30 is permitted by the trapped pipes 31, and from the pocket 28 by the sump 32 and trapped pipe 33.

In operation, the gases to be treated or washed are drawn through the inlet openings 2 and 3, the gas-receiving chambers 19 and the washing chambers 20, and are propelled into the pocket 28 and the outlet 4 by the fan blades 7. The screens 18 serve to distribute the gases flowing into the washing chamber 20 and, being wetted by the spray from the nozzles 8, facilitate the washing of the gases. In the chamber 20 the beater arms 6 moving adjacent to the nozzles 8 serve to effect a thorough commingling of the gases and washing liquid. As the gases are driven through the washer and into the pocket 28, the moisture contained therein is separated by the action of the blade tips and removed through the channels 30.

Various modifications in the arrangement of parts and details of construction may be made without departing from the scope of the invention as defined by the appended claims.

What is claimed is:

1. In a gas washer, the combination of a casing provided with a central gas inlet and a peripheral gas outlet, a screen located adjacent the gas inlet and through which the gas is drawn, a rotative member in the casing provided with fan blades acting to draw the gases through said screen and casing and force the same through said outlet, said rotative member being also provided with beater arms, and spray nozzles in said casing inward of the fan blades and adjacent to the

beater arms on the rotative member for washing the gases after they pass through the screen.

2. In a gas washer, the combination of a casing provided with a central gas inlet and a peripheral gas outlet, means in said casing for washing the gases admitted through said inlet, a screen interposed between said washing means and said inlet, means in said casing, outwardly of the washing means, for forcing the gases radially therethrough from said central inlet and means adjacent the periphery of the casing for eliminating moisture from the gases.

3. In a gas washer, the combination of a casing provided with two opposed central gas inlets and a peripheral gas outlet, a rotative member in the casing defining parallel gas passages from the respective inlets to the outlet and provided with fan blades, the tips of said blades being bent, means in said casing for washing the gases and channels formed in said casing opposite the tips of said fan blades to receive the moisture deflected thereby from the gas stream.

In testimony whereof I have signed my name to this specification.

FREDERICK H. WAGNER.
